UNITED STATES PATENT OFFICE.

CHARLES J. QUILL, OF SAN FRANCISCO, CALIFORNIA, ASSIGNOR, BY MESNE ASSIGNMENTS, TO EDWIN W. BEARDSLEY, TRUSTEE, OF SAN FRANCISCO, CALIFORNIA.

CURRENT-RECTIFIER.

1,252,615.

Specification of Letters Patent. Patented Jan. 8, 1918.

Application filed September 25, 1916. Serial No. 121,998.

To all whom it may concern:

Be it known that I, CHARLES J. QUILL, a citizen of the United States, residing at San Francisco, in the county of San Francisco, State of California, have invented a new and useful Current-Rectifier, of which the following is a specification in such full and clear terms as will enable those skilled in the art to construct and use the same.

10 This invention relates to an improved mechanical electric current rectifying mechanism of a simple and cheap construction, which has no parts likely to get out of order and which cannot be tampered with by unskilled operators. This invention is an improvement on the mechanical pole changer shown in my patent application Serial Number 84,312 filed Mar. 15, 1916.

An object of the invention is to produce 20 a pole changing device capable of being applied to any small self starting synchronous motor now on the market, the quantity of current being rectified being independent of the quantity of current used in the synchronous motor.

Another object of the invention is to produce a very high efficiency rectifier, the only current being lost being that necessary to operate the synchronous motor, and which 30 does not increase with an increased demand on the amount of rectified current supplied, the only other loss being that of the very slight brush friction on the commutator bars.

35 Another object of the invention is to produce a pole changer which will effect the desired rectification of the current with substantially no sparking and without danger of a short circuit should the motor get out 40 of step or stop.

An embodiment of the invention is shown in the drawing in which the same reference numeral is applied to the same portion throughout, but I am aware that there may 45 be many modifications thereof.

Figure 1 is a side elevation of the complete device, a portion of a synchronous motor also being shown,

50 Fig. 2 is a transverse sectional view of the device,

Fig. 3 is a plan view of the completed device,

Fig. 4 is a longitudinal sectional view of the complete device,

Fig. 5 is a view of the right hand end of 55 the pole changer,

Fig. 6 is a plan view of the panel on which the complete apparatus is mounted,

Fig. 7 is a plan view in diagrammatic form of this apparatus applied to storage 60 battery work,

Fig. 8 is a diagrammatic plan view of this apparatus as applied to motion picture work in which the current is used for supplying 65 arc lighting effects, and

Fig. 9 is a diagrammatic form of the device in which two banks of lamps are used in conjunction with the current for supplying the battery.

The numeral 1 indicates a suitable base on 70 which is supported a synchronous motor 2 having suitable construction throughout and having a shaft 3 projecting therefrom upon which this rectifying apparatus is installed.

The rectifier consists of a tubular member 75 4 adapted to be placed on the shaft 3 and which is secured thereto by means of the set screw 5. The tubular member has a shoulder against which a tubular member 6 abuts, the latter being made of suitable fiber or 80 other insulating material. Mounted on the tubular member 6, which is provided with a shoulder similar to that on the tubular member 4, are two contact rings 7 and 8 which are radially positioned with an insulating fiber ring 9 between them. Adjacent the ring 8 there is a fiber ring 10 and also mounted on the tubular member 6 in four adjacent circumferential sets of four 85 each are the sixteen metallic segments 11, 90 said segments being insulated from each other by radially extending portions of the tubular member 6 as indicated at 12 in Fig. 2 and by means of the fiber rings 13, 14, 15 and 16, each of said rings being suitably 95 dovetailed as illustrated in Fig. 4 to hold the segments 11 in place. A washer 18 is used under the nut 19 to bolt all of the rings and the two tubular members 4 and 6 tightly together.

100

A post 20 extends upwardly from the base 1 and is provided with a centering pin 21 for holding the pole changer in the precise position that it should occupy at all times. A set screw 22 holds the screw 21 in a given adjustment.

Adjacent the path of the two rings 7 and 8 are two contact brushes 23 and 24, which brushes are held by suitable posts 25, 26.

- 10 Also adjacent the pole changer there are four posts 27, 28, 29 and 30, each of which is provided with a tubular member 31, 32, 33 and 34, said members carrying suitable contact brushes 35, 36, 37 and 38 adapted to 15 run on the segments 11 ninety degrees apart and on the separate series of segments so that only one brush bears on any one of the groups of four segments into which the sixteen segments, referred to above, are divided when mounted on the commutator.

While there are sixteen segments 11 only eight of them are connected with the rings 7 and 8, wires 65, 66 Fig. 4 being shown connecting to four of the segments, while 25 the wires 67, 68, Fig. 2 are shown connected to two of the other segments. The remaining segments are simply used as a track for the brushes.

In Fig. 7 there is shown the wiring system in detail. In said figure the line wires 30 are indicated at 50, 51 while the feed brushes are shown at 23, 24, the feed rings at 7 and 8, separated by the insulation disk 9.

- 35 A wire 52 leads from the ring 7 to a connection 53 extending to the segments 11^a, 11^b, a similar wire 54 leading to the segments 11^c, 11^d in the next space but one from the first segments and 90 degrees 40 different therefrom. Another wire 55 extends from the ring 8 to wires 56, 57 connected with the contact segments 11^e, 11^f and 11^g, 11^h respectively. It is to be observed (see Figs. 2, 4 and 5) that the inlet 45 wires are placed in holes 61, 62, 63 and 64 in the tube 6, and that the wires two of which are shown at 65, 66 are connected to the alternate segments of alternate series. The wires 67, 68 are similarly connected to 50 alternate segments 90 degrees different from the latter wires and in the other alternate series. The brushes B¹, B², B³, and B⁴ are connected to the wires 60, 61, 62 and 63 respectively, said wires having resistances 55 74, 75 and 76. At 77 there is a polarized relay to show the polarity of the rectified current.

The wires 70 and 73 are joined on one side of the reversing switch 78 while the 60 wires 71, 72 are joined on the opposite side of said switch. The relay 77 has a shunt wire 80 with which the armature 81 may connect to close a circuit through the wires 82, lamp 83 and wire 84 to show the po-

larity of the current delivered. A wire 85, 65 lamp 86 and wire 87 connect the brushes B¹, B³ to act as a direct current pilot light.

The pilot light 83 just mentioned is for the purpose of enabling the operator to know the polarity of the current he may be 70 delivering to the battery since with a battery it is essential that the polarity of the current must be such as will charge the battery and not discharge it, a consideration of little moment in arc lighting machines. The reason of this lies in the fact that it is impossible to determine in advance the polarity of the current that will come off the rectifier when the switches are closed, and if not correct it can be changed 75 to the battery at the switch 78. The pilot light 86 is for the purpose of showing when direct current is flowing.

Now from the foregoing construction it will be seen that when the alternating current rings and split segments are rotated synchronously with the machine producing the alternating current that unidirectional current will be delivered to the battery B which is connected to the reversing switch 90 78 by the wires 88, 89. Since it is impossible in advance to determine the polarity of the unidirectional current the operator must stand ready to shift the reversing switch as soon as a light shows in the 95 lamp 83 to prevent discharging the battery.

The arrangement of the switch board is shown in Fig. 6 in which 90 indicates the base, 83 a lamp having a red globe for indicating the polarity of the direct current, 100 M the synchronous motor, 92 the switch, 93 an ammeter, 94 the double pole reversing switch and 95 the polarized relay.

In Fig. 8 there is shown the wiring for using current for a motion picture arc light. 105 In this figure the numbering is the same as in Fig. 7 except that wires 97, 98, 99 and 100 lead to the reversing switch 78, while wires 101, 102 lead to the arc light 103. The wires 97, 98 have resistances 104, 105 110 and the so-called "current smoothing" coils 107, 106, which latter coils are used to improve the character of the current used on the carbons thereby preventing the noisy hissing often present.

In Fig. 9 there is shown a slightly different system in which the wires 110, 111, 112 and 113 lead to the reversing switch 78, two banks of lamps 114, 115 being used as resistance in the wires 110, 113. In this form 116 there is an automatic polarity corrector 116 cut across the poles of the reversing switch.

The four pole rectifier shown is intended for the rectification of 60 cycle current operating at 1800 revolutions per minute and requires a synchronous motor for that current and number of revolutions per minute.

Having thus described my invention what

I claim as new and desire to secure by Letters Patent of the United States, is as follows, express reservation being made of permissible modifications:

5 1. A current rectifier comprising the combination, with a synchronous motor, of a commutator, comprising a plurality of segments, a pair of alternating current rings, connections between the alternate segments 10 and rings, two alternating current brushes and four direct current brushes bearing on the segments.

2. A current rectifier comprising the combination with a synchronous motor of a 15 commutator adapted to be rotated with the armature and having a plurality of segments in four sets adapted to divide the current between two complete circuits, and brushes to deliver the current unidirectionally to suitable apparatus for the use thereof, which apparatus receives current from both of said circuits.

3. A current rectifier comprising the combination with a synchronous motor of a 25 commutator having four series of segments and two alternating current rings, connections between the rings and oppositely placed alternate segments, and four brushes adapted to contact with the segments to 30 receive direct current therefrom.

4. A current rectifier for transforming alternating into direct current, a pair of alternating circuit wires, two alternating current rings and four series of segments, segments to which each of said wires are led, 35 brushes to take current off said segments, and circuits completed alternately through apparatus to use said current and alternate sets of segments.

40 5. A current rectifying device for changing alternating into direct current consisting of a pair of circuit wires connected with the alternating current supply, a pair of alternating current rings connected with each

45 alternating current wire, four series of commutator segments connected in alternate pairs with the alternate current rings, brushes in contact with said commutators, said brushes being so positioned as to complete a circuit intermittently through alternate segments of said commutator and through a circuit adapted to use the direct current.

6. A current rectifying device comprising 55 a pair of alternating current wires, a plurality of sets of commutator segments to which each of said wires is electrically connected, the segments of each set being positioned 90 degrees different from the segments of the set next adjacent, wires extending from the brushes for each set of segments to an apparatus for using the unidirectional current, brushes to take current from the contact segments and deliver it al-

ternately to the two circuits just mentioned 65 unidirectionally, and a suitable resistance in each of the circuits to prevent the back electromotive force of the apparatus using current from effecting the commutator rings.

7. An alternating current rectifier consisting of a pair of alternating current supply wires, a pair of alternating current rings to which said wires are electrically connected, a plurality of commutator segments having the live segments positioned 70 90 degrees from the live segments next adjacent, two circuits completed to the commutator segments and through an apparatus for the use of direct current, and four 75 brushes bearing upon said commutator segments and connected with the two circuits just mentioned whereby they will receive electric current alternately from the commutator segments.

8. A current rectifying device comprising a pair of alternating current supply wires, two alternating current rings four sets of commutator segments electrically connected with the alternating current rings, a brush for each set of commutator segments positioned 90 degrees from each other 80 brush, an apparatus for using unidirectional current and two complete circuits extending from the brush to the apparatus for using 85 unidirectional current substantially as described.

9. A current rectifying apparatus comprising the combination with a pair of alternating current wires of two alternating current rings electrically connected with each 100 wire, four sets of adjacent commutator segments, brushes bearing upon each set of commutator segments, two complete circuits connected with the brushes, and an apparatus for the use of unidirectional current connected with said two circuits and receiving unidirectional current first from one of said 105 circuits and then from the other.

10. A current rectifying device comprising a pair of alternating current wires, a pair of alternating current rings electrically connected therewith, a plurality of commutator segments in adjacent series, the live segments being 90 degrees different in position from the live segments next adjacent, 110 four brushes in contact with said segments, a pair of circuits completed through said brushes and through an apparatus for the use of unidirectional current, and a polarized relay in one of the brush circuits for determining the direction of the current rectifier.

11. An electric current rectifier comprising a pair of alternating current wires, a pair of alternating current rings with which said wires are electrically connected, a plurality of commutator segments side by side, said segments being connected in alternately po- 115 120 125

sitioned pairs with the two alternating current rings, brushes bearing upon the commutator segments and positioned 90 degrees from each other, two complete circuits extending from the brushes to an apparatus for using unidirectional current, one circuit receiving current alternately with the other, and resistance wires in each of said circuits to pre-

vent the back electromotive force of the apparatus to which the current is being sent ¹⁰ from injuring the brushes and commutator segments.

In testimony whereof I have hereunto set my hand this 15th day of September A. D. 1916.

CHARLES J. QUILL.
